FOOTWEAR

Pearl Y. Smiley, Kitchener, Ontario, Canada, assignor to The B. F. Goodrich Company, New York, N. Y., a corporation of New York

Application December 10, 1936, Serial No. 115,200

4 Claims. (Cl. 36—7.3)

This invention relates to footwear, and especially to footwear of the fur-trimmed galosh or overshoe type.

Such footwear has been constructed heretofore by attachment of the fur trimming strip to the inner face of the upper, but this has had the objection that the ridge of fur at the inner face of the upper rubs against the stocking of the wearer, soiling the latter and wearing the fur.

10 In some cases the fur trimming strip has been attached only at the outer face of the upper but here the edge of the upper has been objectionably exposed. Also the edge of the upper has not been adequately stiff so that unsightly gaping 15 of the margins of the shoe opening has occurred when the shoe has been unlaced, either on or off the foot.

Also, in these prior expedients, the fur strip has been attached at its margin fur side to the 20 upper and then folded over to expose the fur with the result that an appreciable unexposed width of the strip margin has been wasted so far as appearance is concerned.

The chief objects of the present invention are 25 to provide a trimmed article of footwear in which a ridge of the trimming strip is avoided which might rub objectionably against the stocking of the wearer, in which the margin of the upper is adequately stiffened for maintaining an attractive form when the shoe is unlaced, and in which security of attachment is provided with economy of materials and convenience of procedure.

These and further objects will be apparent from the following description, reference being 30 had to the accompanying drawing in which:

Fig. 1 is a perspective view of a fur-trimmed shoe of the galosh type constructed according to and embodying the invention in its preferred form.

40 Fig. 2 is a section of the margin of the upper showing a fur strip attached thereto in accordance with the invention.

Fig. 3 is a similar section showing the preferred complete attachment of the fur strip to the upper, the section being taken along the line 45 3—3 of Fig. 1.

Figs. 4 and 5 are views like Figs. 2 and 3, respectively, but showing a modified construction.

The shoe illustrated in Figs. 1 to 3 comprises 50 an upper 10, preferably of two-ply sheet material, including an inner facing 11 of rubberized fabric adhered to an outer facing 12 which may be of any suitable material such as velvet, suede cloth or the like. The shoe preferably is slit at its front, and for closing it and securing the shoe

upon the foot, eyelets 19, 19, may be provided for suitable lacing.

A fur strip 15 is provided, preferably with a binding strip 13, of fabric or other suitable material, secured about the edge of the strip 15 as 5 by stitching 14. The fur strip is secured in substantially edge-on relation to the edge of the upper preferably by an overcast stitch 17 passing through the fur strip, the binding strip 13 and two plies of the upper 10. The fur strip is then 10 brought outward and downward to present its fur side out at the upper margin of the upper, and preferably the strip is secured at the outer face of the upper by a stitching 18 passing through the strip and upper. 15

This construction has the important advantage that the fur strip is securely attached to the margin of the upper with economy of material, there being no waste-producing lapping of the fur strip for the attachment, and no ridge of the 20 fur is produced at the inner face of the upper such as might rub objectionably against the stocking of the wearer. Also the margin of the upper is well stiffened so that even when it is unlaced its sides tend to close together attractively as shown at 20 in Fig. 1. 25

In the embodiment of Figs. 4 and 5 a binding strip 13a provided about the edge of the upper 10, instead of the fur strip, and this binding strip is secured to the upper by stitching 14a. Overcast 30 stitching 17a secures the fur strip in edge-on relation to the upper, as shown.

In some cases it may be desired to provide two binding strips, one for the fur strip as in Figs. 1 to 3 and one for the upper as in Figs. 4 and 5, 35 the fur part and the upper being secured in edge-on relation as by an overcast stitching passing through both binding strips, the fur strip and upper.

While fur is the preferred material for the decorative strip, other material, such for example as plush fabric, velvet or leather, may be used if desired. The invention is advantageous especially with fur, however, because of the thickness of this material and the desirability of preventing 45 undesirable rubbing of it against the stocking of the wearer.

Variations may be made without departing from the scope of the invention as it is defined in the following claims. 50

I claim:

1. An article of footwear comprising an upper, a fur strip having a binding strip at an edge thereof, the fur strip being secured in substantially edge-on relation of its bound edge to the 55

- edge of the upper by stitches passing through the fur strip, the binding strip and upper, and the fur strip being stitched at its other margin to the outer face of the upper so that the fur-strip 5 is held bent over from the edge of the upper and to the outer face thereof, and, whereas the edge of the upper is concealed by the fur, substantially no ridge of fur is presented to rub against the stocking of the wearer.
- 10 2. An article of footwear comprising an upper, a binding strip at the margin of the upper, and a fur strip stitched in substantially edge-on relation to the edge of the upper, the stitches passing through said binding strip and upper, and the fur strip being bent over at the outer face of the upper from the edge thereof, so that, whereas the 15 edge of the upper is concealed by the fur, substantially no ridge of fur is presented to rub against the stocking of the wearer.
- 15 3. An article of footwear comprising an upper, a binding strip disposed about the edge of the

upper, and a fur strip attached in substantially edge-on relation to the edge of the upper with the binding strip intervening, the stitches passing through the fur strip, the binding strip and the upper, and the fur strip being stitched at its other margin to the outer face of the upper and being thereby held bent down from the edge of the upper to the outer face thereof, so that, whereas the edge of the upper is concealed by the fur, substantially no ridge of fur is presented to 10 rub against the stocking of the wearer.

4. An article of footwear comprising an upper, a fur strip secured in substantially edge-on relation to the edge of the upper and bent over at the outer face of the upper so that the fur at the edge 15 of the upper extends substantially upright and conceals the edge of the upper and substantially no ridge of fur is presented to rub against the stocking of the wearer.

PEARL Y. SMILEY. 20
